Application April 13, 1935, Serial No. 16,120

13 Claims. (Cl. 21—93)

This invention relates to sterilizers and more particularly to sterilizers adapted to sterilize surgical instruments or other medical equipment or supplies.

5 An object of the invention is to provide an improved and efficient sterilizer in which the heat is applied to the articles to be sterilized through the medium of heated air or other gas, rather than through a heated liquid.

10 Another object of the invention is the provision of such a sterilizer having adequate protection against contamination of the sterilized articles both during the sterilizing period and during the subsequent cooling period.

15 Still another object is the provision of such a sterilizer of simple and compact form, easy and relatively inexpensive to manufacture, and sturdy and simple in operation.

To these and other ends the invention resides in certain improvements and combinations of parts, all as will be hereinafter more fully described, the novel features being pointed out in the claims at the end of the specification.

In the drawings:

25 Fig. 1 is a vertical section taken substantially centrally through sterilizing apparatus constructed in accordance with a preferred embodiment of the invention, illustrating the parts in sterilizing position;

30 Fig. 2 is a similar view illustrating the parts in cooling position;

Fig. 3 is a horizontal section through one end of the apparatus, with the parts in sterilizing position;

35 Fig. 4 is a similar view with the parts in cooling position; and

Fig. 5 is a diagrammatic view illustrating one suitable circuit arrangement.

The same reference numerals throughout the 40 several views indicate the same parts.

The apparatus of the present invention includes a suitable sterilizing chamber formed by walls 11 having an extension 12 at one end, and a removable closure 13 for closing a suitable opening 45 through which the articles to be sterilized may be inserted in and removed from the chamber 14 defined by the walls 11. The chamber 14 may conveniently be of approximately rectangular shape with its top open and with the closure 13 removably associated with this top so as to close it completely and seal the chamber when the cover is in normal closed position. Suitable thermal insulation 15 is preferably associated with the cover 13 to reduce transmission of heat 50 through the cover.

The wall portions 11 and 12 are preferably of sheet metal. On the outer end of the extension 12 is suitable thermal insulation 18, and beyond this insulation is a metal plate 19 having an annular shoulder 20.

5 Mounted on the outer side of the plate 19 is an electric motor 25 having its shaft extended through the members 12 and 19 and the interposed thermal insulation 18 and carrying a fan 26 within the extension chamber formed by the member 12. A tight bearing is formed between the motor shaft and the partition members 12, 18, and 19 through which it extends, so that, although the shaft is free to rotate, no air or other gas can pass into or out of the sterilizing 15 chamber through the shaft opening, and the sterilizing chamber remains completely sealed against ingress of air when the cover 13 is in normal closed position.

Within the extension 12 is a holder 30 in which 20 is placed one or more electrical heating elements indicated diagrammatically at 31. The holder 30 does not extend quite to the top of the extension chamber 12, but leaves a space between the top of the holder and the top of the extension chamber through which air may return when the fan 26 is in operation. It will be noted that the fan is in alignment with and behind the heating elements 31 so as to blow air forwardly through these heating elements in the direction of the 30 arrows in Fig. 1.

Walls 35 outside of and spaced from the walls 11 provide a chamber, passageway, or duct 36 extending around the bottom, sides and one end of the sterilizing chamber 14. Still other walls 35 35 37 outside of and spaced from the walls 35 provide an insulating compartment 38 extending around the bottom, sides, and one end of the walls 35, and suitable thermal insulation is placed within the space 38. A conduit 39 connects the 40 cooling duct 36 to the outside atmosphere at the end of the apparatus remote from the motor 25 and heating elements 31, the outer end of this conduit 39 being preferably covered by any suitable screen 40.

Around the motor 25 and some distance outwardly therefrom is a housing member 45 forming, in effect, an extension of the cooling passageway 36, and having a large opening at its outer end and a guiding flange 46 extending inwardly 50 from the opening. A sleeve 47 is suitably mounted in the flange 46 for axial movement therealong, the innermost position of the sleeve 47 being determined by contact of the inner end of the sleeve with the plate 19 immediately around the annular 55.

shoulder 20, as shown in Fig. 1, and the outermost position of the sleeve 47 being determined by a suitable stop such as the screw 48 which comes into contact with the inner edge of the guiding flange 46, as shown in Fig. 2. The outer end of the sleeve 47 is closed by a suitable screen 49.

The outer end of the motor shaft is extended outwardly beyond the motor frame and there carries a second fan 50 which rotates within the space defined by the sleeve 47. When the sleeve 47 is in its innermost position as shown in Fig. 1, the inner end of the sleeve is in substantially air tight engagement with the plate 19 and the sleeve defines a chamber substantially closed at its inner end and open at its outer end at which the screen 49 is located. Under such conditions, with the motor running, the fan 50 simply causes some circulation of air through the screen 49 and within the chamber, to help in keeping the motor cool. When the sleeve 47 is pulled out to its outer position as shown in Fig. 2, however, then the rotation of the fan 50 may draw air inwardly through the screen 49 and cause such air to pass from the inner end of the sleeve 47 through a series of holes or slots 55 in the partition 19, into the space 36 between the walls 11 and 35, and thence through this space to the outlet conduit 39, substantially in the direction indicated diagrammatically by the arrows 60 in Fig. 2.

This circulation of cool air drawn in from the outside by the fan 50 and circulated in the space 36 will rapidly cool the contents of the sterilizing chamber 14, the heat from which is transmitted through and radiated from the walls 11 and is picked up by the cool air flowing through the space 36.

It will now be apparent that the heating or sterilizing operation is performed with the sleeve 47 in its innermost position as shown in Fig. 1. In this position, there is no circulation of air through the space 36, but the motor 25 is running and the heating elements 31 are in operation, with the result that the air within the sterilizing chamber 14 is very rapidly heated to a high degree and the hot air reaches all parts of the sterilizing chamber, due to the circulation produced by the fan 26. When the high temperature has been maintained within the chamber 14 for the required time to produce the desired sterilization, the sleeve 47 is pulled out and the heating elements 31 are turned off, but the motor 25 is allowed to remain running. Thus the fan 26 continues in operation and continues to circulate the air within the sterilizing chamber (no longer being heated by the heating elements) and the heat within this chamber is rapidly carried to the metal walls 11, from which it is radiated or through which it is conducted to the cool air flowing through space 36 under the influence of the fan 50. In this way the sterilizing chamber is rapidly cooled after sterilization, but while the sterilizing chamber still remains entirely sealed and without the ingress of any air from the outside, which might contaminate the articles just sterilized.

In order to prevent any possibility of accidentally keeping the heating elements in operation when the sleeve 47 is pulled out for a cooling operation, it is desirable to provide means for controlling the heating elements by the position of the sleeve 47. This means is best shown in Figs. 3 and 4, and comprises a pair of switch contact members 61 and 62 and a cam 63 on the contact member 62. The electrical circuit to the

heating element 31 passes through the contact members 61 and 62 and is closed only when these two members are in contact with each other. When the sleeve 47 is moved inwardly to the sterilizing position shown in Figs. 1 and 3, the sleeve operates upon the cam 63 to close the contacts and thus place the heating elements 31 in operation. When the sleeve 47 is pulled outwardly to the cooling position shown in Figs. 2 and 4, then it releases the cam 63 and the contacts 61 and 62 spring open to disconnect the heating elements automatically.

Preferably a thermostat control is provided for all or a part of the heating elements so that these heating elements will automatically maintain the desired temperature in the sterilizing chamber. A thermostatic control switch of any conventional type is indicated diagrammatically at 65 and is settable to different temperatures by means of an accessible setting knob 66. The heat responsive part of the thermostat is indicated at 67 in Figs. 1 and 2 and is preferably located behind the fan 26, as this is the coolest part of the sterilizing chamber and thus the thermostat will be responsive to the minimum temperature in the chamber rather than to the maximum temperature, which condition is highly desirable in sterilizing apparatus.

Preferably also the thermostatic control does not shut all of the heating elements 31 on and off, but controls only a part of them. As shown diagrammatically in Fig. 5, the thermostatic switch 65 controls only the portion 31a of the heating elements, shunting this portion out of operation when the predetermined temperature 35 is exceeded, and causing continued operation of this portion 31a when the temperature falls below the predetermined temperature at which the thermostatic switch has been set. The portion 31 of the heating element which is not controlled by the thermostatic switch is so designed as to have sufficient capacity to maintain the sterilizing chamber at approximately a steady or even sterilizing temperature when once the chamber has been brought up to this temperature. Thus when the sterilizing operation is commenced, all of the heating elements will be in operation to bring the chamber up rapidly to the desired temperature, but when once this temperature has been attained, the portion 31a of the heating elements which is controlled by the thermostatic switch will be put out of operation automatically, and the unaffected portion 31 of the heating elements will substantially maintain the desired temperature, perhaps allowing it to drop slightly, with the result that the thermostatic switch will have to operate only occasionally to bring the portion 31a into play briefly to maintain the desired temperature during the sterilizing period.

A time switch indicated diagrammatically at 70 is preferably also provided, so that the entire apparatus will be shut off at the end of a predetermined time even if the operator should forget it. This time switch may be of any conventional construction and is designed to turn off the electrical circuit at the end of such period after it is turned on, as will be sufficient to bring the sterilizing chamber up to sterilizing temperature and to complete the sterilizing operation. Then, after the time switch has operated, the operator may pull out the sleeve 47 to the cooling position shown in Figs. 2 and 4, and may again turn on the time switch to start the cooling operation. If the sterilizing chamber is sufficiently cooled before the entire time switch period has 75

elapsed, there is, of course, nothing to prevent the operator from opening the cover 13 and removing the sterilized articles.

Inasmuch as the temperature variations to which the walls 11 are subjected are substantially greater than those to which the walls 35 and 37 are subjected, it follows that the expansion and contraction of the walls 11 will be greater than that of the walls 35 and 37. Consequently, the walls 11 are preferably not rigidly connected to the walls 35 and 37, but a space 75 (Figs. 1 and 2) may be left between the walls 35 and 37 and the walls 11 at the top of the apparatus to allow for the difference in expansion or contraction, and also to prevent direct conduction of heat from the walls 11 to the walls 35 and 37. The upper edges of the walls 11 may be bent outwardly to form horizontal flanges resting on blocks or strips 76 of thermal insulation.

20 It will now be seen that with the improved sterilizer of the present invention, the sterilizing chamber is completely sealed at all times when in use, both during the sterilizing operation and during the subsequent cooling operation. This 25 is a feature of great importance, since any ingress of air for purposes of cooling would be likely to cause contamination of the sterilized articles.

While the sterilizing chamber 14 would be 30 merely filled with air in the simplest form of apparatus, yet it is within the scope of the present invention to perform the sterilizing operation in an atmosphere of gas other than air. For example, if it is desired for any reason, a 35 conduit may be connected to the sterilizing chamber to fill it with carbon dioxide, nitrogen, or other inert gas after the articles have been placed in the chamber and the cover has been closed, and the term "gas" as used in this specification 40 and in the accompanying claims is intended to be construed broadly as including both ordinary atmospheric air and any other gases.

Also it is apparent that not only air, but any other suitable gas, or, indeed, any suitable fluid, 45 may be used in the cooling passageway 36. The term "fluid" as here used is intended in its broad sense as including both liquids and gases.

The insulation 18 in the partition between the sterilizing chamber and the motor assists in reducing transmission of heat from the sterilizing 50 chamber to the motor and thus helps to keep the motor cool at all times.

While one embodiment of the invention has been disclosed, it is to be understood that the 55 inventive idea may be carried out in a number of ways. This application is, therefore, not to be limited to the precise details described, but is intended to cover all variations and modifications thereof falling within the spirit of the invention or the scope of the appended claims.

I claim:

1. A sterilizer comprising walls and a movable closure forming a sterilizing chamber sealed against ingress of air when said closure is closed, means for heating and circulating gas within said chamber to sterilize articles therein, and means for circulating gas around said chamber in external contact with certain walls thereof to cool the interior of said chamber.
2. A sterilizer comprising walls and a movable closure forming a sterilizing chamber sealed against ingress of air when said closure is closed, one of said walls having relatively high heat conductivity, electrical heating means within said chamber, and means for circulating gas around

said chamber in external contact with said wall of relatively high heat conductivity, to cool the interior of said chamber.

3. A sterilizer comprising walls and a movable closure forming a sterilizing chamber sealed against ingress of air when said closure is closed, one of said walls having relatively high heat conductivity, electrical heating means within said chamber, means for circulating heated gas within said chamber, and means for circulating gas around said chamber in external contact with said wall of relatively high heat conductivity, to cool the interior of said chamber.

4. A sterilizer comprising walls and a movable closure forming a sterilizing chamber sealed against ingress of air when said closure is closed, electric heating means within said chamber, fan means also within said chamber, means forming a duct separated in a substantially gas tight manner from and in heat-exchanging relation to said chamber, and fan means for circulating gas through said duct to cool said chamber.

5. A sterilizer comprising walls and a movable closure forming a sterilizing chamber sealed against ingress of air when said closure is closed, electric heating means within said chamber, fan means also within said chamber, means forming a duct around said chamber in heat-exchanging relation with a substantial part of the walls thereof, means tending to circulate gas through said duct to cool said chamber, movable means for controlling flow of gas through said duct, and means operated by said movable means for controlling said electric heating means.

6. A sterilizer comprising walls and a movable closure forming a sterilizing chamber sealed against ingress of air when said closure is closed, electric heating means within said chamber, fan means also within said chamber, motor means outside of said chamber for driving said fan means, heat insulating means between said chamber and said motor means, means forming a duct around said chamber in heat-exchanging relation with a substantial part of the walls thereof, and other fan means also driven by said motor means to tend to circulate gas through said duct to cool said chamber.

7. A sterilizer comprising means forming a sterilizing chamber, means forming a cooling chamber in external contact with said sterilizing chamber throughout a substantial area, means for heating the interior of said sterilizing chamber, and means for circulating cooling fluid through said cooling chamber to cool the interior of said sterilizing chamber.

8. A sterilizer comprising means forming a sterilizing chamber, means forming a fluid passageway having a portion thereof in contact with a wall of said sterilizing chamber throughout a substantial area, heating means within said sterilizing chamber, a motor within said passageway, a fan within said sterilizing chamber driven by said motor, and a second fan in said passageway driven also by said motor to cause flow of fluid to said motor for cooling said motor and to tend to cause flow of fluid through said passageway to cool said sterilizing chamber.

9. A sterilizer comprising means forming a sterilizing chamber, means forming a fluid passageway having a portion thereof in contact with a wall of said sterilizing chamber throughout a substantial area, heating means within said sterilizing chamber, a motor within said passageway, a fan within said sterilizing chamber driven by said motor, a movable sleeve surrounding said

- motor and effective when in one position to close said passageway at a point beyond said motor, and a second fan in said sleeve driven also by said motor to direct fluid against said motor to cool said motor when said sleeve is in closed position and to cause flow of fluid past said motor and on through said passageway when said sleeve is in open position, to cool said motor and also to cool said sterilizing chamber.
10. A sterilizer comprising means forming a sterilizing chamber, means forming a fluid passageway having a portion thereof in contact with a wall of said sterilizing chamber throughout a substantial area, heating means within said sterilizing chamber, a motor within said passageway, a fan within said sterilizing chamber driven by said motor, a movable sleeve surrounding said motor and effective when in one position to close said passageway at a point beyond said motor, a second fan in said sleeve driven also by said motor to direct fluid against said motor to cool said motor when said sleeve is in closed position and to cause flow of fluid past said motor and on through said passageway when said sleeve is in open position, to cool said motor and also to cool said sterilizing chamber, and means controlled by movement of said sleeve from closed position to open position for rendering said heating means ineffective.
15. A sterilizer comprising means forming a sterilizing chamber substantially completely sealed from access of external air during both heating and cooling operations, means for heating the interior of said chamber to sterilize arti-

cles therein, means for cooling the interior of said chamber without disturbing the sealed condition thereof, to cool sterilized articles without contaminating them, said cooling means including a cool fluid duct in heat exchanging relationship to said chamber, valve means for controlling flow of fluid through said duct, means for automatically rendering said heating means inoperative upon opening said valve means, and means for agitating the gas within said chamber both during operation of said heating means and during operation of said cooling means, to promote rapid heating or cooling, respectively, of all of the gas within said chamber.

10. A sterilizer comprising means forming a sterilizing chamber substantially completely sealed from access of external air during both heating and cooling operations, means for heating the interior of said chamber, means forming a gas duct in heat exchanging relationship to said chamber, means for circulating cool gas through said duct to cool the interior of said chamber, and means for agitating the gas within said chamber during the circulation of the cool gas through said duct, to promote the rapid cooling of all of the gas within said chamber.

15. A sterilizer according to claim 12, in which said means for circulating cool gas through said duct is a fan located externally of said sterilizing chamber, and in which said means for agitating gas within said chamber is another fan located within the chamber, further including a single motor for driving both of said fans.

CHARLES R. MEITZLER.
